UNITED STATES PATENT OFFICE

1,948,657

LINER FOLDING DEVICE

John Lee Ferguson, Joliet, Ill., assignor to J. L. Ferguson Company, Joliet, Ill., a corporation of Illinois

Application July 23, 1930. Serial No. 470,091

20 Claims. (Cl. 93—2)

My invention relates to folding devices and more particularly to folding devices for use in connection with container sealers whereby a container inner lining is to be folded and sealed 5 simultaneously with the container sealing operation.

It is now common practice to use moisture proof inner linings for containers in which certain materials are packed. These inner linings 10 are usually made of waxed paper or similar thin, moisture proof, and often transparent or translucent material, in the form of a bag of such dimensions that it will fit snugly inside the empty container, and of such length that the open end 15 may be folded together and glued to form a moisture proof container lining after the material has been inserted therein.

Heretofore, it has been necessary to fold and seal the inner linings, by hand, independently 20 of the container flaps which are folded automatically in their passage through a suitable container sealer. This method is laborious, expensive, unsanitary and generally unsatisfactory.

In my invention I provide an efficient method, 25 and automatic means for practicing the method of folding and sealing the lining and container simultaneously, during the passage of the filled packages through a container sealer. Furthermore, by the use of my method, the linings are 30 uniformly and accurately sealed in such manner that the lining is secured in the container by being glued between the flaps.

My invention may be built into and form an integral part of a container sealer, or it may be 35 in the form of a small, compact, self-contained unit which may be easily attached to and used in connection with existing container sealers. In the latter case, especially it is desirable to fold the lining and container simultaneously in such 40 manner that the position of the lining will not interfere with the application of adhesive to the container flaps.

Other objects and advantages will be apparent 45 from the specifications and the appended claims.

In the drawings:

Figure 1 is a top plan view of the device in 50 connection with the glue roller and supporting parts of a container sealer;

Fig. 2 is a longitudinal section taken on a line 55 corresponding substantially to line 2—2 of Figure 1;

Fig. 3 is a fragmentary perspective view of the opening and folding members in cooperative position with a container; and

Fig. 4 is a perspective view of one of the open

containers, a portion being broken away to better illustrate the lining.

Referring to the drawings in detail, the embodiment shown comprises a frame 1, on which all of the component parts are assembled to form 60 a unit which is supported on the side frames 2 and 3 of a container sealer. The side frames also support a pair of glue rollers 4 mounted in bearings 5 and 6, and which may be constantly driven from any desired power source by means of a 65 bevel gear 7.

The unit comprises opening devices for opening the side flaps, and other members for simultaneously closing the end flaps or ears so that the lining will automatically be folded outwardly 70 and inwardly to the position shown in Fig. 3, in which position they are held by the rotating end-flap folding means until the container passes under a retaining guide and roller from which it passes under the glue roller, and from which 75 latter the flaps receive an adhesive and are later folded and sealed by the usual container sealer folders which are not shown in the present instance.

The containers are carried on the usual container sealer conveyors and move consecutively through the machine in the direction of the arrow in Figure 1, where their position is indicated by dotted lines.

The folder unit includes a transverse shaft 8 85 mounted in suitable bearings in the frame 1 and driven from a shaft 9 through a pair of bevel gears 10. The folding means also includes rotary and oscillating folder members driven from the shaft 8, and which cooperate with the flaps of 90 the moving containers, and it is, therefore, obvious that their movement must be synchronized with the speed of the container. It is, therefore, desirable, though not essential, that the drive shaft 9 be driven from a suitable power source 95 connected with the container conveyor.

The filled containers are passed under and adjacent the folding unit, and during their movement the side flaps 11 of the container 12, together with the lining 13, are folded outwardly 100 as shown in Fig. 3, by spaced rotary folder arms 14 and 15, which rotate in opposite directions and are secured to longitudinal shafts 16 and 17, respectively. These shafts are supported in bearings in the frame 1, and the shaft 16 is driven from the transverse shaft 8 by beveled gears 18, and the shaft 17 is driven from the same shaft by beveled gears 19.

The rear end flap 20 and the lining adjacent thereto are folded inwardly and simultaneously 110

with the outward folding of the side flaps 11, by means of horizontally rotating folder and retaining blades 21 and 22 secured to vertical shafts 23 and 24, respectively. The shaft 23 is driven 5 from the side folder shaft 16 through beveled gears 25, a vertical stub shaft 26 and gears 27 and 28 on the shafts 26 and 23, respectively. In a similar manner the shaft 24 is driven from the side folder shaft 17 by a transmission comprising 10 a pair of bevel gears 29, a stub shaft 30, and gears 31 and 32 on the shafts 30 and 24, respectively.

The rotary movement of the end folder plates is considerably faster than the forward movement of the container. Therefore, the end flap 20 15 will be folded inwardly, as shown in Fig. 3, simultaneously with the outward folding of the side flaps by the arms 14 and 15, by means of the upturned ends 33 of the folder plates, and during the continued rotation of the latter, they 20 will pass over the outwardly folded side flaps 11 and retain them in position to pass under the retaining guide plate 34, which latter is provided with upturned edges 35 for guiding the flaps thereunder. The plate 34 is secured to a tongue 25 or guide extension 36, which latter is supported on shaft 39 by means of a bearing bracket 37 thereon. The extension guide 36 extends forwardly in alignment with the moving containers for the purpose of retaining the folded end flaps 30 in position to pass under the glue rollers, after which the side flaps are folded inwardly, thereby sealing the container by any suitable folding mechanism.

The side flaps are also held in position to pass 35 under the glue roller, and the lining is pressed snugly in the position shown in Fig. 3, by means of the rollers 38 on the shaft 39, which latter is driven from the shaft 8 by means of gears 40.

The glue rollers 4 are so positioned, relative 40 to the path of the moving container, that substantially all of that portion of the liner overhanging the side flaps 11 together with the exposed portion of the side flaps is coated with adhesive during the passage of the container under 45 the glue rollers. It has been found unnecessary to apply adhesive to the end flaps 20 and 20a and no adhesive is applied to that portion of the side flaps under the overhanging liner. The adhesive dries very quickly and has no tendency 50 to get on the material in the container. However, when desired, the end flaps 20 and 20a may be made to overlap and completely close the container.

In order that the front end flap 20a may be 55 folded simultaneously with the operations previously described, I provide an oscillating arm 41 pivoted at 42 and extending downwardly to engage and fold the container flaps 20a when the arm is moved to a position indicated by 60 dotted lines in Fig. 2, the forward movement of the container and the rearward movement of the arm 41 cooperating to fold the end flap 20a simultaneously with the folding of all of the other flaps. These synchronized folding operations 65 assure the accurate and uniform folding of the inner lining 13.

The arm 41 is provided with a forwardly extending shoe or tongue 43 for the purpose of retaining the end flaps in folded position and 70 guiding them under the retaining plate 34. The arm is operated and synchronized relative to the other operating parts of the device by means of a cam 44 secured on the shaft 8 and cooperating with a roller 45 on a link 46, which latter is pivoted at 47 on the arm 41. The roller 45 is held

in engagement with the cam, and the arm 41 is moved rearwardly by a spring 48 secured thereto, and the link 46 is guided by the shaft 8 in a slot 49.

In operation the containers are supported on 80 suitable chairs 50, as shown in Fig. 3. These chairs are of the usual type and secured in spaced relation on the usual container sealer conveyor chains, as shown in my United States Patents Nos. 1,423,095 and 1,423,096. During the passage 85 of the containers through the sealer, the folding arms 14 and 15, and the folding and retaining plates 21 and 22 are constantly rotated, and the movements of these arms, together with the oscillation of the arm 41, are so synchronized with the consecutively-moving containers that each 90 container, with its associated lining, is folded as shown in Fig. 3. After being glued with the flaps in this position, the side flaps are folded inwardly by the usual folder, thus cementing the 95 folded ends of the lining securely between the end and side flaps.

The containers are usually inverted for filling, and the folding operation, as described, is performed on the bottom so that when the containers 100 are opened from the top the previously sealed end of the inner lining is disclosed, the bottom of the lining being secured in the container as described.

The physical embodiment shown and described 105 may be varied without departing from the spirit of the invention, and I desire, therefore, to be limited only by the prior art and the scope of the appended claims.

Having thus described my invention, what I 110 claim and desire to secure by Letters Patent of the United States is:

1. The method of sealing filled containers having unattached liners therein, comprising simultaneously folding the side flaps and adjacent unattached portions of the lining outwardly, and the end flaps and adjacent unattached portions of the lining inwardly, then applying adhesive to the exposed portions of the side flaps and overhanging portions of the lining, then folding 115 the side flaps inwardly to cause the lining to be sealed therebetween.

2. The method of sealing lined containers of the character described having unattached liners therein, comprising folding the end flaps with a portion of the unattached lining thereunder and simultaneously folding the side flaps and unattached lining outwardly so that when the side flaps are sealed a portion of the lining will be between the end flaps and one of the side flaps and 125 the opposite portion of the lining will be between the side flaps.

3. The method of folding container flaps and unattached lining for passage through a sealer, comprising simultaneously folding some of the flaps and juxtaposed portions of the lining outwardly and some of the flaps and juxtaposed portions of the lining inwardly to a horizontal plane so that portions of the lining are folded 135 upon themselves and on the outturned flaps and portions of the lining are under the inturned flaps.

4. A unit for manipulating container flaps and unattached lining for passage through a sealer, comprising a plurality of synchronized moving 145 members for simultaneously folding the end flaps and juxtaposed portions of the lining inwardly and side flaps and juxtaposed lining outwardly.

5. A unit for manipulating container flaps and unattached lining for passage through a sealer, 150

- comprising a plurality of synchronized moving members for simultaneously folding the lining and one set of opposed flaps inwardly and the lining and another set of opposed flaps outwardly. 14. A method of folding a carton and lining, said carton having four flaps at one end thereof and said lining having a rectangular tubular portion lying adjacent and inside of said flaps, said method comprising exerting pressure on two opposite flaps to press them toward each other and against the juxtaposed portions of the lining to fold the flaps and juxtaposed lining portions toward each other and exerting pressure against the inside of the tubular lining at portions juxtaposed to the other two flaps to spread these portions. 80
6. The combination with a container sealer having an adhesive applying means, a combined container and lining folding device for folding container flaps and unattached linings comprising a self-contained unit having means thereon for folding the flaps together with juxtaposed portions of the lining of consecutively moving containers in opposite directions, means for synchronously controlling said folding operations, and means for guiding said folded flaps adjacent said adhesive applying means. 10 15 14. A method of folding a carton and lining, said carton having four flaps at one end thereof and said lining having a rectangular tubular portion lying adjacent and inside of said flaps, said method comprising exerting pressure on two opposite flaps to press them toward each other and against the juxtaposed portions of the lining to fold the flaps and juxtaposed lining portions toward each other and exerting pressure against the inside of the tubular lining at portions juxtaposed to the other two flaps to spread these portions. 85
7. A device of the character described comprising a plurality of means for folding moving container flaps simultaneously with unattached linings in opposite directions, means for synchronizing the folding operations, and means for retaining said flaps and lining in folded position during the further movement of said container. 20 25 14. A method of folding a carton and lining, said carton having four flaps at one end thereof and said lining having a rectangular tubular portion lying adjacent and inside of said flaps, said method comprising exerting pressure on two opposite flaps to press them toward each other and against the juxtaposed portions of the lining to fold the flaps and juxtaposed lining portions toward each other and exerting pressure against the inside of the tubular lining at portions juxtaposed to the other two flaps to spread these portions. 90
8. A device of the character described comprising a plurality of means for folding the flaps of moving containers, together with juxtaposed portions of the unattached lining in opposite directions for passage through a sealer, means for synchronously driving all of said means, said folding means being arranged to hold said flaps in folded relation during further movement of said containers. 30 14. A method of folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the lining to fold said flaps and juxtaposed lining portions toward each other, and means for exerting pressure against the inside of the tubular lining at portions juxtaposed to the other two flaps to spread these portions. 100
9. A device for folding the flaps and unattached linings of moving containers, comprising a plurality of means for folding said flaps and juxtaposed portions of said linings in opposite directions, said means cooperating with said flaps to fold the linings diagonally across the corners thereof. 35 14. A method of folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the lining to fold said flaps and juxtaposed lining portions toward each other, and means for exerting pressure against the inside of the tubular lining at portions juxtaposed to the other two flaps to spread these portions. 110
10. A device of the character described comprising a plurality of combined container flap and unattached lining folding means, one of said means arranged to fold a side flap and the adjacent portion of the unattached lining outwardly, and another of said means arranged to fold an end flap and the adjacent portion of the unattached lining inwardly, both of said last means cooperating to fold said lining diagonally simultaneously with the folding of said flaps. 40 45 14. A method of folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the lining to fold said flaps and juxtaposed lining portions toward each other, and means for simultaneously exerting pressure against the inside of the tubular lining at portions juxtaposed to the other two flaps to spread these portions. 115
11. A device of the character described comprising means for folding the end flaps of moving containers on lines transverse the line of movement of said containers, means for folding the unattached side flaps on lines parallel with the line of movement of said containers, all of said folding operations cooperating to fold the unattached lining of said container on diagonal lines during the flap folding operation. 50 55 14. A method of folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the lining to fold said flaps and juxtaposed lining portions toward each other, and means for exerting pressure against the inside of the tubular lining at portions juxtaposed to the other two flaps to spread these portions, said second pressure exerting means comprising a pressure exerting member rotatable about an axis parallel to the axis of the last said flaps. 125
12. In a container sealer, the combination of a glue roller for applying adhesive to the folded flaps of consecutively moving cartons, a plurality of means rotating in a horizontal plane for folding end flaps and linings, means rotating in a vertical plane for folding side flaps and linings, oscillating means for holding end flaps and linings, all of said means cooperating to fold said flaps rectangularly and to simultaneously fold said lining octagonally. 60 65 14. A method of folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the lining to fold said flaps and juxtaposed lining portions toward each other, and means for exerting pressure against the inside of the tubular lining at portions juxtaposed to the other two flaps to spread these portions, said first pressure exerting means comprising a pressure exerting member rotatable about an axis parallel to the axis of the last said flaps. 130
13. The process of sealing filled containers and unattached liners comprising simultaneously folding container flaps and lining in a manner to cause portions of the liner to be interset between the flaps during the folding, and applying adhesive during the folding to simultaneously seal the container and lining. 70 75 14. A method of folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the lining to fold said flaps and juxtaposed lining portions toward each other, and means for exerting pressure against the inside of the tubular lining at portions juxtaposed to the other two flaps to spread these portions, said first pressure exerting means comprising a pressure exerting member rotatable about an axis parallel to the axis of the last said flaps. 140

exerting means comprising a pressure exerting member rotatable about a vertical axis.

5 20. Apparatus for folding a carton and lining, said carton having four flaps at one end thereof and said lining having a rectangular tubular portion lying adjacent and inside of the flaps, said apparatus comprising means for exerting pressure on two opposite flaps to press them toward each other and against the juxtaposed portions of the 10 lining to fold said flaps and juxtaposed lining

portions toward each other, and means for exerting pressure against the inside of the tubular lining at portions juxtaposed to the other two flaps to spread these portions, said first pressure exerting means comprising a pressure exerting member rotatable about a vertical axis and said second pressure exerting means comprising a pressure exerting member rotatable about an axis parallel to the axis of the last said flaps.
